(57) CLAIM

The ornamental design for an inflatable device, as shown and described.

DESCRIPTION

FIG. 1 is a perspective view of an inflatable device.

FIG. 2 is a front view of an inflatable device.

FIG. 3 is a rear view of an inflatable device.

FIG. 4 is a top view of an inflatable device.

FIG. 5 is a bottom view of an inflatable device.

FIG. 6 is a right side view of an inflatable device; and,

FIG. 7 is a left side view of an inflatable device.

The broken lines in the drawing are for illustrative purposes only and form no part of the claimed design.
